UNITED STATES PATENT OFFICE

132,707

DESIGN FOR A PLAQUE

John W. Ziegler, Garden City, N. Y.

Application January 9, 1942, Serial No. 105,093

Term of patent 7 years

To all whom it may concern:

Be it known that I, John Wm. Ziegler, a citizen of the United States, residing at 133 Wickham Road, Garden City, in the county of Nassau and State of New York, have invented a new, original, and ornamental Design for a Plaque, of which the following is a specification, reference being had to the accompanying drawing, forming part thereof.

Fig. 1 is a plan view of the plaque, showing my new design.

Fig. 2 is an edge elevational view of a plaque showing my new design.

The rear of the plaque is substantially plain.

The drawing is shaded to show color.

The characteristic features of my design reside in the portions shown in solid lines.

I claim:

The ornamental design for a plaque, as shown and described.

JOHN W. ZIEGLER.
